RADIO-TELEPHONE

Marcus S. Lessner, Chicago, Ill., assignor to Utica Communications Corp., Chicago, Ill., a corporation of Illinois

Filed Jan. 24, 1961, Ser. No. 63,667

Term of patent 7 years

(Cl. D26—14)

Fig. 1.

Fig. 2.

Fig. 3.

FIGURE 1 is a perspective view of a radio-telephone embodying my design;

FIG. 2 is a rear elevational view of the device shown in FIG. 1; and

FIG. 3 is an end elevational view as seen from the left of FIG. 2.

The right end of the casing is plain and the same as the left end shown in FIG. 3, except for the microphone detachably mounted on the latter.

The dominant features of my new design are shown in solid lines in the drawing, the broken line microphone cord being omitted from FIGS. 2 and 3 for convenience in illustration.

I claim:

The ornamental design for a radio-telephone, as shown and described.
